GAS VALVE SAFETY SHUTOFF

Ernst R. Koppel, Chicago, Ill., assignor to A. O.
Smith Corporation, Milwaukee, Wis., a corpora-
tion of New York

Application June 2, 1945, Serial No. 597,263

4 Claims. (Cl. 158—117.1)

1

This invention relates to a gas valve safety shut off and has been applied to pilot controls in thermostatically operated water heaters of the type in domestic use.

The principal object of the present invention is to provide a gas valve safety shut off for a pilot control that is absolutely positive.

Another object is to provide an interlock between the main gas cock and the pilot push button valve so that the latter cannot be operated unless the cock is in pilot position.

Another object is to provide a control which fails "safe."

These and other objects and advantages of the invention will appear in connection with the description of an embodiment of the invention illustrated in the accompanying drawing.

In the drawing:

Figure 1 is a front elevation of the control;

Fig. 2 is a side elevation;

Fig. 3 is a vertical sectional view of Fig. 2 in which the main gas cock is at start position to permit flow of gas from the inlet to the pilot push button valve which is in depressed position;

Fig. 4 is a section taken on line 4—4 of Fig. 3 with the push button depressed;

Fig. 5 is a transverse section of the valve through the lock pin taken on line 5—5 of Figure 1 with the push button valve in locked position;

Fig. 6 is a similar view showing the push button valve in unlocked position;

Fig. 7 is a view similar to Fig. 4 with the push button released;

Fig. 8 is a detail view taken on line 8—8 of Fig. 5 showing the cam in the valve knob; and

Fig. 9 is a section taken on line 9—9 of Fig. 6.

The valve construction to which the present invention is applied is similar to that found in the application of the present inventor filed August 14, 1941, entitled "Safety pilot for heaters" and issued to Patent No. 2,384,314 on October 4, 1945.

In general, as shown in the drawings, the valve unit comprises a cast metal body 1 having two main valve chambers, one for the gas cock or manual shut off valve 2 and the other for the thermostatically controlled snap valve 3.

A pilot burner 4 is threaded at its inner end into the casing 1 and a thermostat 5 extending parallel to the pilot burner tube 4 and above it is also threaded into the casing. The central rod 6 of the thermostat is connected to and operates valve 3. The thermostatic control is similar in general to present day standard thermostat controls used on the main burner for water heaters.

The hand shut off valve has a handle 7 for turning it and is inscribed at three positions properly spaced apart with the markings "off," "start" and "on" in the order named. "Pilot"

2

may be substituted for "start," if desired. The marking "off" refers to the main shut off valve 2 being in closed position. The marking "on" refers to the valve 2 in open position to permit flow of gas to the main gas burner.

The body portion 8 of valve 2 is conical and has a radial passage 9 therein disposed to register with a gas inlet passage 10 when handle 7 is at "on" position as shown in Fig. 9 and to be turned so as to fail to register with the passage 10 when handle 7 is at "off" position as illustrated in Fig. 5. Passage 9 is always in registry with the outlet passage 11 in the valve 2 and casing 1.

The conical body 8 is also provided with an auxiliary passage 12 positioned to connect inlet passage 10 to passage 13 leading to pilot push button valve 14 when handle 7 is at "start" position as shown in Fig. 3.

The radial location of passage 12 relative to port 9 is such that when handle 7 is at "start" passage 9 is shut off from passage 10 and passage 12 registers with inlet 10 and passage 13 leading to pilot push button valve 14. Inlet passage 10 is closed to both passages 9 and 13 when handle 7 is turned to "off" position as illustrated in Fig. 5. The passage 10 is also open to passage 13 to allow gas to flow to the push button valve 14 when handle 7 is at "on" position. The flow of gas to the pilot is therefore not interrupted in turning the gas cock valve 2 from "start" to "on" position. When at "on" position the valve 14 is released to shut off flow of gas thereto from passage 13. Passage 13 still receives gas from passage 10 but is inoperable to supply gas to the pilot burner at the on position of handle 7.

The gas for the main burner passes through inlet 10, passage 9, outlet 11, and through valve 3 to pipe 15 leading to the burner control valve. Both valve 2 and thermostatically controlled valve 3 must be open to supply gas to the main burner. Since valve 3 is controlled by heat from the pilot burner 4, it shuts off the entire gas supply in the event the pilot flame is extinguished.

The push button valve 14 is a pilot valve operated manually by a push button 16 which preferably is non-circular in cross section and passes through a complementary opening in casing 1 to prevent turning of the valve body 17 thereof. The cylindrical valve body 17 of the valve is normally biased outwardly by a spring 18 at its rear end. The body 17 has a longitudinal passage 19 extending from its rear end to a line near its forward end where connection is made by passage 19 with a passage 20 extending diametrically through the valve body. Two radial passages 21 and 22 connect with passage 19 intermediate the rear end of body 17 and the passage 20.

When push button 16 is depressed or pressed inwardly as shown in Fig. 4, moving valve body 17

against spring 18, passage 20 is caused to register with a passage 23 leading from the gas supply passage 13 and with a passage 24 leading to the pilot burner 4. Both radial passages 21 and 22 are closed when button 16 is in depressed position. When pilot thermostat 5 becomes heated and valve 3 snaps open button 16 can then be released. A needle valve 25 controls the volume of gas supply to the pilot burner 4.

When the pilot burner and the main burner are on, the radial passage 21 registers with passage 26 leading from the low pressure side of thermostat valve 3 and radial passage 22 registers with passage 23 which in turn connects with passage 24 leading to the pilot burner 4. At the same time passage 20 is closed by the housing surrounding the valve body 17.

Valve body 17 may be provided with a bleeder groove 27 intermediate radial passages 20 and 22 which alternately register with port 23. This groove is of such a length that it has only a small overlap narrower than the diameter of port 23. In transferring valve 14 from the depressed to the release position gas will bleed through groove 27 and since the overlap is not sufficiently wide the passages 20 and 22 will be open simultaneously momentarily to port 23, allowing for uninterrupted gas flow to pilot 4.

The actual operation of the valve structure is described in co-pending application issued to Patent No. 2,384,314, previously referred to and need not be further described here.

Reference is made to the interlock between the main gas cock or shut off valve 2 and the pilot push button valve 14 to prevent operation of the pilot button 16 in the "on" and "off" position of the gas cock.

The interlock in general comprises a rod or interlock plunger 28 connected to a cam 29 on the underside of handle 7 of gas cock 2 by a head 30 and extending horizontally from handle 7 within an opening in casing 1 to the pilot push button valve 14.

The plunger 28 is provided with flange 31 intermediate the ends thereof and is spring loaded by spring 32 which is retained between flange 31 and the outer plate 33. Plate 33 also holds in place the body of the main shut-off valve 2. The inner end 34 of plunger 28 is generally pointed and normally serves as a detent entering a transverse groove 35 in valve body 17 of valve 14 by reason of spring 32 biased against plate 33. In this position of plunger 28 it is impossible to depress button 16.

Cam 29 on the underside of handle 7 extends from the "on" position of handle 7 to the "off" position through the "start" or pilot position thereof and operates to limit radial movement of handle 7 and the turning of valve body 8. In the operation of the interlocking device, head 30 of the plunger 28 rides in the cam track as the handle 7 is turned from the off position toward the start position and is lifted against spring 32 by cam 29 when the "start" position is reached. This pulls plunger 28 out of groove 35 in valve body 17 and permits button 16 to be depressed by the operator. A detent 36 may be provided at the center of the cam 29 to indicate the "start" position.

If the handle 7 of main valve 2 is then turned from "start" to "on" position while the push button 16 is held depressed, the plunger upon release of the push button is spring-pressed back into groove 35, locking the push button in released position.

At the "off" position of handle 7 the end 34 of plunger 28 also enters the groove 35 in valve body 17 interlocking the push button 16 in release position. It is therefore necessary in order to manually depress push button 16 and permit the flow of gas to the pilot 4 from the passage 13, to turn the main valve 2 to "start" position.

Passage 13 in turn is in registry with passage 12 leading to high-pressure inlet 10 when handle 7 is at either "start" or "on" position to carry inflowing gas to the push button valve 14. At the "on" position push button 16 cannot be depressed from released position. Gas to the pilot is then flowing from the lower pressure side of thermostatic valve 3, and plunger 28 locks the push button against operation.

The invention provides a one hundred per cent safety shut-off for a gas pilot control that adds to the safe operation of a thermostatically operated domestic water heater or other heater with which it may be employed.

Various embodiments of the invention may be employed within the scope of the accompanying claims.

I claim:

1. In a safety control for gas heaters having a main burner, a pilot burner, and a safety shut off valve operated thermostatically in response to a flame from said pilot burner to open position for supplying gas to the pilot burner and the main burner, the combination of a manually operable pilot valve to supply gas to the pilot burner when said safety shut off valve is closed, a main shut off valve having a handle to move the same between "closed," "start" and "open" positions to supply gas to said pilot valve when in start position, and a plunger connected by a cam to said handle at one end and extending into a groove in said pilot valve at the other end, said plunger being removed from said groove by said cam when the main shut valve is turned by said handle to "start" position to provide for operation of said pilot valve and disposed in said groove when the main shut off valve is turned by said handle to "closed" and to "open" positions to prevent operation of said pilot valve.

2. In a safety control for gas heaters having a manually operable pilot valve to initially supply gas to a pilot burner, and a manually operable main shut off valve, a handle on said shut off valve to turn the same to "closed", "start" and "open" positions, a plunger extending between said handle and the pilot valve, a head on the outer end of said plunger, a cam groove in the underside of said handle disposed to confine said plunger head and to control the longitudinal position of said plunger at all times in correlation to the rotary position of said handle, and means to interlock the plunger and said pilot valve to prevent movement of the latter from closed to open position when said main valve is turned to "closed" or "open" position by said handle and to release said interlock when said main valve is turned to "start" position.

3. In a safety control for gas heaters having a manually operable pilot valve to initially supply gas to a pilot burner, and a main shut off valve, a handle on said main shut off valve to turn the same to "closed", "start" and "open" positions, a plunger secured at one end to a cam on said handle and disposed for longitudinal movement to engage and disengage said pilot valve, said plunger being pulled outwardly by said cam when the handle is turned to "start" position, to dis-

engage the plunger from said pilot valve and permit manual operation of the latter, and means biasing said plunger inwardly when the handle is turned to "closed" or "open" position to engage said pilot valve and lock the same against manual operation thereof.

4. In a safety control for gas heaters having a main shut off valve and a manually operable pilot valve, a detent plunger adapted to engage said pilot valve and lock the same in closed position against operation, a spring normally pressing said plunger into locking engagement with the pilot valve, a handle for operating said main shut off valve, and a cam operated by the movement of said handle and engaging said plunger to lift the same out of locking position and against said spring to release the pilot valve for

operation when said main shut off valve is in a predetermined position for lighting the pilot.
